M. F. FITZGERALD

VIBRATOR HORN

Filed Aug. 24, 1920

M. F. Fitzgerald Inventor

Sturtevant and Mason Attorneys

UNITED STATES PATENT OFFICE.

MAURICE F. FITZGERALD, OF WINSTED, CONNECTICUT, ASSIGNOR TO THE FITZGERALD MFG. CO., OF TORRINGTON, CONNECTICUT, A CORPORATION OF CONNECTICUT.

VIBRATOR HORN.

Application filed August 24, 1920. Serial No. 405,698.

To all whom it may concern:

Be it known that I, MAURICE F. FITZGERALD, a citizen of the United States, residing at Winsted, in the county of Litchfield, State of Connecticut, have invented certain new and useful Improvements in Vibrator Horns, of which the following is a description, reference being had to the accompanying drawing and to the figures of reference 10 marked thereon.

This invention relates to vibrator horns, and more particularly to the electrically operated type.

One of the objects of this invention is to provide a simple device of few parts arranged compactly and capable of producing an effective signal.

Another aim of this invention resides in constructing and arranging the solenoid 20 armature so that it will also act as a means for actuating the sound diaphragm.

Still another aim of this invention resides in arranging the solenoid armature so that it will not only operate the sound diaphragm but it will also operate the make and break devices for the same.

Another object of this invention resides in suitably mounting the solenoid, the combined armature and diaphragm striker, and the circuit breaker upon a common base plate within the horn casing.

These and other objects will in part be obvious and will in part be hereinafter more fully disclosed.

Referring more particularly to the accompanying drawing:

Figure 1 represents a side sectional view of the complete horn;

Fig. 2 represents a plan view with the cover removed;

Fig. 3 is a section through the mounting for the contact devices;

Fig. 4 is a perspective view of the combined armature and striker, and

Fig. 5 is a perspective view of the two parts of the circuit breaker.

Referring more particularly to the accompanying drawing, the horn comprises a casing 1 having bolted thereto the flange 2, by which it may be secured to any desirable part of an automobile. At its front portion, the casing 1 is provided in any suitable manner, with a trumpet or horn proper 3, while at the back portion, the casing is provided with a removable cover 4 held to

the casing by means of bolts 5 and 6. The usual sound diaphragm 7 extends across the mouth of the horn 3 and is secured at its periphery to the wall of the casing 1 by means of a series of bolts 8.

In order to secure a compact arrangement and provide a construction involving a minimum number of parts, the magnet 9 for operating the diaphragm striker is mounted within the casing with its core 10 substantially parallel to the plane of the diaphragm, and a combined armature and diaphragm striker is pivotally mounted within the casing so that the armature portion 11 thereof lies across and adjacent to the core 10, while the diaphragm striker portion 12 thereof lies in proximity to and directly over the center of the diaphragm. In order to effect this arrangement, the armature and striker portions of the member are arranged at an angle to each other.

The preferred manner of mounting the magnet 9 and combined armature and striker member within the casing consists in providing a plate or base 13 spaced from the diaphragm 7 at its periphery by means of suitable spacing members 14, through which bolts 15 pass.

This plate is preferably made of sheet metal and is suitably slotted as at 16 to provide a rather broad tongue which, when bent at right angles to the base of the plate, forms an upstanding flange 17 to which is attached, in any desired manner, as by means of a rivet 18, the magnet 9. By bending upwardly this flange 17 there is thus formed a suitable opening 19 in the plate providing an aperture, permitting the free operation of the circuit breaker members as hereinafter described.

It is also preferred to pivotally mount the combined armature and diaphragm striker on this base plate, and to this end, the plate is slotted as at 20 and 21, and the resilient tongues rolled back on themselves to provide a pair of spaced journals 22 and 23 adapted to receive the pivotal pins 24 and 25 of the combined armature and diaphragm striker.

The base plate 13 is also provided with an additional aperture 26 which is adjacent to and connects with the aperture 19. The contact portion 12 of the armature member passes through these apertures 26 and 19 in order to permit it to lie immediately over

the end of one member of the circuit breaker device.

The armature 11 is resiliently held in delicately adjusted position in proximity to the core of the magnet in any desired manner, the preferred construction is shown in the drawings, in which a leaf spring 27 is secured to the base plate 13 by means of one of the bolts 15, and is held normally pressed 10 against the outer face of the armature 11. Another leaf spring 28 is likewise attached to the base plate 13 as by means of the bolt 5 and projects across the base beneath the striker member 12, and acts to press the 15 same upwardly. By means of the combined action of these two springs, the integral armature 11 and striker member 12 are maintained in adjusted position.

The circuit breaker is composed of an 20 outer contact member 29 having the usual adjustable contact 30 and the lower contact member 31 having an upstanding contact 32 adapted to make electrical connection with the end of the contact 30. These members 25 29 and 31 are separated as usual by an intermediate insulation strip 33, and the lower contact member 31 is again insulated as by means of the strip 34 from a leaf spring 35 which projects outwardly across the slot 19 30 and lies with its tip 36 under the end of the striker 12. As shown clearly in Fig. 3, the contact members 29 and 31, and leaf spring 35, and also the intermediate insulation members are all held in position by means of 35 bolts 37 and 38 passing through the base. Suitable electric leads are taken from the contact members 29 and 31 as by means of the ears 39 and 40, and the electrical connection leading from the ear 40 is in turn 40 connected to the contact post 41 on the casing. The other wire 39 is connected by the ear 40 to the winding of the magnet, and the other end of this winding is in turn connected by the wire 42 to a second contact 45 post 43 on the casing.

In the operation of the device, when the magnet is energized, the armature is attracted to cause the striker portion 12 to contact against the sound diaphragm to create a signal. At the same time, the projecting end of the striker 12 depresses the leaf spring 35 of the contact member to cause the separation of the contacts 30 and 32 to break the circuit through the magnet, at 50 which time, the springs 27 and 28 return the armature to its former position, and this cycle of operation is repeated as long as the exterior horn circuit is closed.

It will be seen that the horn as above disclosed is a most advantageous construction, since it provides a compact arrangement. By constructing the armature and diaphragm striker integral and arranging them at an angle to each other, it is possible 60 to pivotally mount either member between

the magnet and the diaphragm, and it is possible to mount the magnet parallel to the diaphragm and to arrange the armature with the integral striker thereof between the solenoid and diaphragm. Furthermore, 70 by extending the striker member 12 across the face of the diaphragm and arranging one member of the circuit breaker beneath the same, so that the circuit will be automatically interrupted by the operation of the combined armature and diaphragm striker, a horn is thus provided of a minimum of parts and arranged in a minimum space. It is also evident that by this arrangement and by means of the resiliently balanced armature and striker member in 75 which the springs 27 and 28 are arranged on opposite sides of the pivotal members 24 and 25, the armature is attracted very 80 easily and quickly.

It is obvious that minor changes in the details of construction and the arrangement of parts may be made without departing from the spirit of the invention as set forth 85 in the appended claims.

Having thus described the invention, what I claim as new and desire to secure by Letters Patent, is:—

1. A vibrator horn comprising a casing 90 having a diaphragm, a supporting sheet metal plate arranged in said casing in spaced relation to said diaphragm, said plate having a struck up portion thereof forming an integral upstanding flange and an adjacent opening, a magnet mounted on 95 said flange, a member pivotally mounted on said plate and having an armature portion arranged to be actuated by said solenoid, and a striker portion adapted to pass through the opening in said plate and contact said diaphragm.

2. A vibrator horn comprising a casing having a diaphragm, a supporting sheet metal plate arranged in said casing in spaced relation to said diaphragm, said plate having a struck-up portion thereof forming an integral flange and an adjacent opening, a magnet mounted on said flange, a member pivotally mounted on said plate and having an armature portion arranged to be actuated by said magnet, and a striker portion adapted to pass through the opening in said plate to contact said diaphragm, and a circuit breaker mounted on said plate and having a portion extending under the striker member to be actuated thereby, said opening in said plate being suitably arranged beneath said breaker to permit its free operation by the striker.

3. A vibrator horn comprising a casing having a diaphragm, a plate mounted in said casing parallel to and spaced relative from said diaphragm, a diaphragm striker mounted on said plate extending across the face of the diaphragm substantially parallel 130

lel thereto, a magnet mounted on said plate for operating said striker, a circuit breaker for said magnet, including a member also extending across said diaphragm substantially parallel thereto with its free end under the projecting end of said striker and adapted to be operated thereby, said plate being suit-

ably apertured to permit the free ends of the striker and circuit breaker to pass therethrough.

In testimony whereof, I affix my signature.

MAURICE F. FITZGERALD.
